Int. Cl. D29—99

U.S. Cl. D72—1

FIG. 1 is a front elevation view of a back plate for a traffic signal light incorporating my new design.

FIG. 2 is a rear elevation of the back plate for a traffic signal light depicted in FIG. 1.

FIG. 3 is a side elevation view of the back plate for a traffic signal light depicted in FIG. 1.

FIG. 4 is an end elevation view of the back plate for a traffic signal light depicted in FIG. 1.

FIG. 5 is an enlarged sectional view taken along line 5-5 of FIG. 1.

FIG. 6 is an enlarged sectional view taken along line 6-6 of FIG. 1.

The stippling is partially shown in FIGS. 1, 2 and 3 for convenience of illustration, it being understood that the stippling is continuous over said surfaces.

I claim:

The ornamental design for a back plate for a traffic signal light, substantially as shown and described.
